INVENTOR.
CHARLES D. SMITH.
BY Richard B. Owen

ATTORNEY.

UNITED STATES PATENT OFFICE.

CHARLES D. SMITH, OF NEW YORK, N. Y.

SIGNAL-CONTROL TRAIN STOP.

Application filed November 21, 1922. Serial No. 602,394.

To all whom it may concern:

Be it known that I, CHARLES D. SMITH, a citizen of the United States, residing at New York city, in the county of New York 5 and State of New York, have invented certain new and useful Improvements in Signal-Control Train Stops, of which the following is a specification.

This invention relates to safety devices 10 for rolling stock and more particularly to a novel and improved mechanism for automatically short circuiting a control switch or generator and applying the brakes to the car if the same passes a predetermined point. 15 Various devices have been made and installed on electric and steam railway cars to prevent collision and to more effectively maintain the block signal system wherein the car or train is rendered inoperative if 20 it leaves the block before the signal is given to do so but many accidents occur on account of the signals sometimes not being seen by the operator or the wrong signal indicated. The object of my invention therefore is to 25 avoid collisions due to the above inefficiency of the block signal system by energizing a contact rail positioned at a predetermined point in a block whereby should the car be driven beyond this point and into the next block, the motor will be immediately rendered inoperative and the compressed air brakes automatically applied, so as to stop the car.

One of the objects of my invention is the 30 provision of a device of the above character wherein a contact rail may be energized from a signal point including a contact shoe to be carried by the car for controlling an automatic cut off connected to the motor or operator's switch and simultaneously actuating a release valve in the 35 compressed air brake system so that the car may be stopped if the same passes what may be termed the danger point far within an occupied block in the block signal system.

Another object of my invention is the provision of an automatic device of this character which can be easily modified for 40 installation on a steam train whereby the power can be automatically cut off and the pneumatic brakes applied in the same manner to stop the train should the same pass a predetermined point in the block signal 45 system.

I accomplish the above objects and others which will become more apparent as the description proceeds and when taken in connection with the accompanying drawings, constituting a preferred embodiment of my invention and wherein:

Figure 1 is a view showing the invention installed on a railway car including the contact rail which completes the circuit to actuate the mechanism.

Figure 2 is a front view of the mechanism in connection with the valve to apply the brakes.

Figure 3 is a side view of the operating mechanism, the casing and panel being shown in section.

Figure 4 is a detail view showing the circuit maker and breaker.

Figure 5 is a detailed view of the locking connection for the actuating rod and

Figure 6 is an end view thereof.

Figure 7 is a modified form of the invention.

Referring now to the drawings wherein like reference characters designate corresponding parts throughout the several views, in Figure 1, I have shown a conventional type of electric railway car having a front compartment for the operator and in which there is shown the control lever 5 and the leads or conductors to an electrified third rail 6. A pipe or conduit 7 is also shown to indicate a portion of the pneumatic air brake system, it being observed that the conductors above referred to and the pipe 7 extend to my automatic trip mechanism designated in its entirety by numeral 8 suitably mounted and accessible to the operator and constructed and arranged in the manner now to be described 95 in detail.

At certain points in the block signal system, a contact rail 9 is positioned which can be energized through a switch 10 at a point located in a signal tower, for instance, (not shown) and the conductors 11 from any position from a signal station, the said contact rail being herein referred to as the danger point in the line, beyond which the car or train should not proceed unless the track ahead is clear and open. A contact shoe 12 carried by the car or train which is in contact with the rail 9 will of course be energized when the switch 10 is closed and the conductor 13 connected to the contact 110

shoe 12 will consequently also be energized to operate the trip mechanism now to be described. The conductor 13 leads to the trip mechanism 8 and a return conductor 5 is grounded to the frame of the car.

The trip mechanism consists of an insulated plate 15 secured by screws or other fastening elements 16 to the wall of the car and preferably accessible to the operator. A 10 second plate 17 preferably of metal is also secured by screws 18 and the screws 16, the last mentioned plate being formed with bearings 19, 20, disposed in spaced relation and parallel with each other, the bearing 19 15 having attached thereto, a supporting bracket 21, for supporting the magnetic coils 23, 26 and the bearing 20 pivotally supporting the armature 22^a. The conductor 13 leads to a binding post 23^a of one coil and the re- 20 turn conductor which is grounded to the frame, is connected to a binding post of the second coil. A spring controlled actuating rod 26 extending through the brackets 19, 20, is provided with an enlarged extension 27 25 at the lower end thereof which extension is provided with a curved cam slot 28 to receive the head 29 of a rotatable valve 30 operable in the valve casing 31 whereby the compressed air may be released through the 30 conduits 32 and the brakes applied. Mounted on the actuating rod 26 and between the brackets, I have provided a coil spring 33 which normally maintains the said actuating rod downwardly when it is in the locked 35 position at which instance, the valve 30 is closed. In order to release the actuating rod, so that it will move upwardly and open the valve 30, the locking pin 34 which engages the notch 36 in the actuating rod must be 40 released. In order to effect this operation, the armature 22^a is adapted to trip the arm or extension 34^a disposed at right angles to the pin 34. The said arm 34^a is adapted to lie within a notch or slot 35^a of a small bar- 45 rel 36^a. Within the barrel and connected to the pin 34, I provide a compression spring 37 which is adapted to release the pin 34 when the said arm 34^a is released from the notch above referred to. It will thus be 50 seen that when this tripping action takes place, the actuating rod moves upwardly, thus operating the valve 30.

The conductors 40, 41, leading to the motor or the control lever of the operator, are 55 connected to the binding posts 42, of the spring contacts 43 secured to the insulated plate 44. The upper end of the actuating rod 26 carries a head 45 preferably of fibre or insulation being secured thereto by a 60 screw 46 or other fastening element. The fibre head 45 carries a contact plate 47 which completes the circuit between the spring contacts when the actuating rod is in its uppermost or normal position as clearly shown 65 by Figure 2 of the drawing.

It will thus be seen that the device is automatic and effective when the circuit is completed to open the valve to apply pneumatic pressure to the brakes and at the same time open the circuit of conductors 41 leading to the motor and control lever whereby power is cut off. In order to conceal the operative mechanism, I have provided a casing 50 having a hinged cover or closure 51 and a catch 52 for locking said cover and 70 when it is desired to set the mechanism in its operative position, by raising the said cover 51, the operator may press down on the head 45 until the pin 34 is engaged in the notch or recess 36, in which position of course, the contact arm 22^a is disengaged from the poles 80 of the magnetic coils.

While I have shown the mechanism and one operative means of completing the circuit through the contact rail 9, and a live rail, it will be readily recognized that various mechanisms may be resorted to to accomplish the same purpose and if so desired the conductors 11 may be connected up with the light signals or operated through a storage battery by the signal operator or the device can be equally connected up with the semaphore, used in the block signal system. My invention, however, is more particularly directed to the trip mechanism shown more in detail in Figures 2 and 3 of the drawings wherein the simultaneous action of cutting off the power and applying the brakes is disclosed.

In a modified form of the invention as disclosed by Figure 7, with but a slight modification the trip mechanism may be installed on a steam train so that the power may be cut off should the train pass a predetermined point. In this form of the invention, the head 45 and the spring contacts 43 are dispensed with and leading from the contact shoe 12^a, I have provided a conductor 13^a leading to the coils 23^a and a second conductor 24^a being grounded. The same arrangement of the spring controlled actuating rod 26^a and the extension 27^a is provided for operating a valve 31^a interposed in the steam pipe or line leading to the steam chest and in this form of the invention also, when the circuit is completed in the manner as above indicated, the valve 31^a will be opened and the pneumatic brakes applied, all of which operate in the same manner as heretofore explained.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

Having thus described my invention, what I claim as new and desire to secure by United States Letters Patent is:—

1. A safety device of the class described comprising a support, bearings mounted on the support, a slidable element including a circuit breaker at one end and a valve actuating member at the opposite end, coils supported on the bearings, a contact arm cooperating with the coils, resilient means for maintaining the slidable element in a set position and lying in the path of movement of the contact arm said slidable element being releasable to simultaneously break the circuit and open the valve when the magnet is energized.

2. A safety device of the class described comprising a support, bearings mounted on the support, a resiliently controlled rod hav-

ing a circuit breaker at its upper end and an enlarged extension at the lower end thereof slidable in the bearings, said extension having a cam slot and connected to a valve for actuating the same to a closed or to an open position, magnets also mounted on the bearings, a pivoted contact arm cooperating with the magnets, means for retaining the rod in a set position, said last mentioned means lying in the path of movement of the contact arm whereby as the rod is released the circuit is simultaneously broken and the valve opened.

In testimony whereof I affix my signature in presence of two witnesses,

CHARLES D. SMITH.
